CALCULATING MACHINE

Albert I. Richards, Sacramento, Calif., assignor to
Friden Calculating Machine Co., Inc., a corpora-
tion of California

Application March 12, 1937, Serial No. 130,501

19 Claims. (Cl. 235—75)

The present invention relates to calculating machines, and more particularly to improved means for controlling the sign character of the registration in the revolutions counter.

5 It is the general object of the invention to provide for selectively determining registration in the revolutions counter of a calculating machine in a single sense irrespective of changes in the sign character of registrations in the ac-
cumulator.

10 Another object of the invention is to provide a calculating machine which is constructed to facilitate the calculation of the gradients of roads, and other similar types of calculation.

15 Another object of the invention is to provide an improved revolution counter mechanism for calculating machines in which the sign character of the registration can be controlled to be like or unlike that of the registration, in the accumu-
20 lator, or which can be controlled independently of the character of registration in the accumula-
tor.

25 Other objects will be noted from the following description of a preferred embodiment of the invention, as illustrated in the accompanying drawings, in which:

30 Figure 1 is a fragmentary vertical longitudinal section through the rear part of the machine, and is taken in a plane indicated by the line 1—1 in Figure 2. Certain of the parts are illus-
35 trated schematically.

Figure 2 is a sectional plan view of the rear part of the machine with the register carriage and the keyboard mechanism removed.

35 Figure 3 is a fragmentary enlarged view showing a part of the counter actuating mechanism in perspective.

Figure 4 is a fragmentary sectional view of a part of the counter mechanism, the view being indicated by the line 4—4 in Fig. 1.

40 Figure 5 is a side elevational view of the revolutions counter control mechanism, as viewed from the right side of Fig. 2. In this view the parts are shown as positioned to determine positive registration in the revolutions counter irrespective of positive or negative registration in the accumulator.

Figure 6 is a fragmentary view of a part of the counter control mechanism and associated parts.

50 Figure 7 is a fragmentary elevational view, similar to Fig. 5, but showing the parts as positioned to provide for registrations of opposite sign character in the counter and the accumu-
55 lator.

55 Figure 8 is a view similar to Fig. 7, with the

parts positioned to determine registrations of like sign character in the counter and the accumu-
lator.

While my invention may be used in various types of calculating machines capable of performing the four cardinal rules of calculation, and in which the sign character of the registration in the revolutions counter can be controlled, I prefer to employ my invention in connection with the type of machine disclosed in the co-
pending applications of Carl M. F. Friden Serial No. 724,482, filed May 8, 1934, and Serial No. 66,381, filed February 29, 1936, which type of machine is commonly referred to as the "Thomas" type, and employs a shiftable accumulator, and "one-way" actuating mechanism for both the accumulator and the revolutions counter.

In the embodiment chosen for illustrative purposes, the calculating machine may include a base 10 (Fig. 1) upon which side frame plates 11 and 12 may be secured, and between which cross plates 13, 14, 15 and 16 may extend to support various parts of the selecting, actuating, and transfer mechanisms for both the accumulator and the revolutions counter. Cross plates 13 and 16 may also carry suitable rollers journaled thereon to support a register carriage 17 in which both the accumulator and the revolutions counter are mounted for endwise shifting movement relative to the frame and the actuating mechanism therefor, which are mounted in the frame.

The accumulator or product register comprises a series of ordinarily spaced similar numeral wheels 21 (Fig. 1), each of which is carried by a vertical numeral wheel shaft 22 carrying a ten tooth bevel gear 23 at its lower end for co-operation with either of similar plus-minus gears 24, 25 formed at the ends of a spool 26. Each spool 26 is slidably and non-rotatably mounted on a square shaft 27, which may be suitably mounted in the cross plates 13, 14 and 15 to carry parts of the transfer and selecting mechanisms. Between the plates 14 and 15, each shaft 27 carries a pair of ten-toothed gears 28 slidably and non-rotatably mounted thereon. Each gear 28 is provided with a grooved hub which is engaged by the forked end 29 of a selecting slide 31, two of which are provided in each order. The slides 31 extend toward the front of the machine for cooperation with an associated bank of numeral keys 32.

The numeral keys 32 may be suitably mounted for endwise sliding movement and at their lower ends have pins 33 for cooperation with differentially inclined cam surfaces 34 of the slides 31.

a part of the keys of each bank being associated with each slide 34 of an order. The arrangement is such that one of the gears 28 is differentially positioned upon depression of a selected numeral key with respect to an associated actuating cylinder 36 (Fig. 1) which may carry two sets of stepped teeth for cooperation with the respective gears 28. Two cylinders 36 for adjacent orders of the machine may be mounted on the same actuating shaft 39 which is suitably journaled in cross plates 14 and 15. As seen in Fig. 2, the shafts 27 are equally spaced and each pair thereof is associated with an actuating shaft 39 are spaced slightly to either side thereof.

15 At its forward end each actuating shaft 39 may be connected by a set of bevel gears 40 with a transversely extending drive shaft 41 which is suitably journaled by bearings 42 in the side plates 11 and 12. Shaft 41 projects beyond the side plate 12 and may be associated with a cyclic clutch or with a cyclically operable hand crank, as may be desired.

20 The above described arrangement is such, that upon one rotation of drive shaft 41, from one to nine increments of movement may be imparted to the shafts 27 of the various orders in accordance with the positioning of the gears 28 with respect to the stepped teeth of the cylinders 36 on the shafts 39. This differential movement 25 of the shafts 27 is transmitted to the numeral wheels 21 from either gears 24 or gears 25 of the spools 26, whose position is controlled to determine whether the registration is positive or negative.

30 To control the meshing of the plus-minus gears 24 and 25 with numeral wheel gears 23, a transversely extending strap 46 (Figs. 1 and 2) extends beneath the spools 26 and between the sets of gears 24 and 25. Strap 46 may be carried for 35 rocking movement by arms 47 pinned on transverse shaft 48 suitably journaled in side plates 11 and 12. Control shaft 48 (Figs. 2 and 5) extends beyond the side plate 12 and carries an upright arm 49 which is connected by bolt 51 40 with a plus-minus slide 52 which extends forwardly of the machine as seen in Fig. 5, and is supported for endwise movement by arm 49 and by link 53. The endwise movement of plus-minus slide 52 to move the plus-minus gears 24, 45 25 in either direction from their central inactive position shown in Fig. 1 may be effected by any suitable means, as, for example, the plus and minus keys shown in said application Serial No. 724,482 or the reversible hand crank shown in 50 said application Serial No. 66,381.

55 Suitable tens transfer and resetting mechanisms may be associated with the accumulator, but as these mechanisms are of conventional construction, they will not be described.

60 The revolutions counter may comprise a series of numeral wheels 61 (Fig. 1), each of which is carried by a shaft 62 suitably journaled in the carriage 17. A numeral wheel 61 is provided for 65 each ordinal position of the carriage and actuating means are associated therewith to introduce an increment of movement to the numeral wheel 61 aligned with the counter actuator as determined by the ordinal position of the carriage, while suitable transfer means is associated with 70 the counter actuator to effect the tens transfer in the higher orders. As described later, the counter actuating mechanism is constructed to effect both positive and negative registration on 75 the numeral wheel 61 as controlled by the sign

character of the registration on the accumulator and the setting of a manual control.

Each shaft 62 of the revolutions counter is provided with a ten toothed gear 63 (Fig. 1) for cooperation with the actuating mechanism, which 5 comprises a tooth 64 (Figs. 1 and 2) which is journaled on a shaft 65 for rocking movement thereabout, and for endwise movement therewith as will be explained. The tooth 64 is supported for two oscillatory movements, one of which is 10 about its axis to move into the plane of the aligned gear 63, and the other of which is axial to effect the movement of the gear 63 for one increment. By changing the phase relationship between the rotative and axial oscillations of the 15 actuator tooth, the increment of movement can be imparted either positively or negatively thru the gear 63 to the associated numeral wheel 61 as will appear more clearly hereinafter.

20 The actuator unit for the revolutions counter as illustrated in Figs. 1 to 4 comprises the digitation actuator tooth 64, and a series of transfer teeth 66 which are formed on respective hubs 67 and 68 pivotally mounted in end to end relation between end collars 69 pinned on the shaft 65. 25 Each actuator tooth and its hub are similar except for the digitation actuator 64 and its hub 67 which are at the right in Fig. 2 and comprise the lowest order. Each hub 68 has at its right end adjacent the lower order, an offset tooth 71 lying 30 in the plane of the actuator tooth of next lower order and held in spaced relation therefrom by a lug 72. Each actuator tooth 64 and 66 is provided with a laterally extending arm 73 which lies under a rod 74 extending between frame yokes 35 76 integrally formed with the collars 69. Between the opposite ends of the yokes 76, a rod 77 is secured, and from which springs 78 extend to the apertured ears 79 of actuator teeth.

40 From the above description, it is seen that actuator tooth 64 and each transfer tooth 66 are each urged in a clockwise direction as viewed in Fig. 1 by springs 78, but are restrained from movement by the engagement of their respective arms 73 beneath the rod 74. It follows, therefore, that the digitation actuator tooth 64 and the transfer actuator teeth 66 will be urged yieldably to active position upon clockwise movement of the framework comprising shaft 65, yokes 76 and rods 74 and 77, the means for producing such 50 movement being described later. Tooth 64 is moved to active position for each rotative oscillation of shaft 65, its yieldable connection to rods 74 and 77 preventing jamming if tooth 64 should accidentally strike a tooth of the aligned gear 63. 55

55 Each transfer tooth 66, however, is held against movement to active position except when the numeral wheel 61 of next lower order passes from nine to zero or zero to nine and thereby determines the transfer of an increment. For this 60 purpose, shaft 62 of each numeral wheel 61 carries a disc 80 (Figs. 1 and 4) formed integrally on the hub of the associated gear 63, and which normally is engaged upon oscillation of shaft 65 by the control tooth 71 of the transfer actuator 65 66 of next higher order. Each disc 80 is provided with a peripheral notch 80a, which, when the associated numeral wheel passes from nine to zero or zero to nine, moves into alignment with control tooth 71 so that such tooth can move into 70 the notch and its associated transfer tooth 66 can move into mesh with the aligned gear 63 and transmit the transferred increment thereto during the axial reciprocation of shaft 65 as described hereinafter.

Because of the overlapping relation of each control tooth 71 with the transfer tooth 86 of next lower order, each transfer tooth is also restrained against movement to active position until the next lower order tooth 86 moves to active position, thereby enforcing a successive transfer from the lowest to the highest order.

Means are provided for rocking the counter actuator frame back and forth about its axis in a timed relation with the operation of the accumulator actuating means, so that tooth 64 is moved to and from active position during each cycle of operation of the machine. Shaft 65, which is both slidably and rotatably journaled by bearings 81 in the side plates 11 and 12, carries adjacent its left hand end, a depending arm 82 (Figs. 1 and 2) which at its lower end has a pin 83 projecting thru an aperture in side plate 11 for engagement with the bifurcated upper end of a bell crank 84 pivoted at 85 (Fig. 1) on plate 11. The other arm of the bell crank 84 carries a suitable pin or roller 86 which is engaged with a cam track 87 (Figs. 1 and 2) in a cam disc 88 secured on the end of the drive shaft 41. Thus, upon each revolution of the drive shaft 41, the cam disc 88 oscillates the bellcrank 84 so that the actuator tooth 64 is given a rotative oscillation in a timed relation to the operation of the accumulator actuating means.

As explained above, the actuator tooth 64 is also given an axial oscillation for effecting the actuation of the gear 63 after the tooth has been brought into registry therewith by the rotative movement thereof. For this purpose, shaft 65 (Figs. 1 and 2) carries a square collar 91 having downwardly projecting pin 92 engaging the bifurcated end of a lever 93 which is formed integrally with a yoke 94 mounted for vertical sliding movement in a pair of brackets 95 on the side plate 12. Thus, oscillation of yoke 94 and lever 93 will effect endwise movement of the shaft 65 and axial oscillation of the actuator tooth 64.

It will be apparent that if the tooth 64 is moved to active position before its endwise movement, the associated numeral wheel 61 will be rotated in one direction, and that, conversely, if the actuator tooth 64 is moved to active position after its endwise movement in one direction, and before its return movement, the numeral wheel 61 will be rotated in the opposite direction. This varying of the phase relationship of the oscillatory movements of the actuator tooth is controlled by the vertical positioning of the yoke 94, the pin 92 being of sufficient length to cooperate with the lever 93 in all positions of the yoke 94. The yoke 94 has an arm 97 (Figs. 1 and 2) at its lower end opposite an arm of the lever 93. Lever 93 and arm 97 carry respective pins 98 and 99 which are disposed on opposite sides of a cam drum 101 for cooperation with the respective cam grooves 102 and 103 thereof.

The cam grooves 102 and 103 are similar, except that they are rotatively displaced about the drum 101 so that oscillation of the yoke 94 will occur at different times in the cycle of revolution of the actuating means in accordance with the engagement of pin 99 with groove 102 as shown in Fig. 1, or the engagement of pin 98 with the groove 103, if the yoke is moved downwardly from the position shown in Fig. 1. The difference in timing provided between grooves 102, 103, effects the initial endwise movement of shaft 65 of the counter actuator either before or after the tooth 64 is moved to active position

by rocking about its axis. In this way the sign character of the registration on the numeral wheel 61 may be reversed.

The position of the yoke 94 is controlled normally by the setting of the plus-minus gears 5 with respect to the accumulator to determine either positive or negative registration. For carrying out this control, the yoke 94 is provided with an annular groove 106 (Fig. 1) which is engaged by a pin 107 (Figs. 1, 2 and 6) carried by an arm 108 secured on a rock shaft 109 journalled in the side plate 12 and a supporting plate 111 suitably mounted in spaced relation from the plate 12. Exteriortly of the plate 111, shaft 109 (Figs. 2 and 5) carries a three arm 15 lever 112 having upper and lower bifurcated arms 113 and 114, and horizontal centralizing arm 116. The end of arm 113 is recessed for engagement by a roller 117 carried by centralizing lever 118 pivotally mounted on a stud 119 on the plate 111, and urged to active position by a spring 120.

The bifurcated arms 113 and 114 (Fig. 5) are adapted for engagement by respective pins 121 and 122 carried at the forked front end of a control arm 123 pivotally secured at 124 to the rear end of plus-minus slide 52. It will be recalled that slide 52 is moved endwise in one or the other direction from its central neutral position shown in Fig. 5 to control selectively positive or negative registration in the accumulator. Thus, the lever 112 will be rocked upon movement of the plus-minus slide 52, and because pins 121 and 122 can be operatively engaged with lever 112 selectively on opposite sides of the pivotal axis thereof, the direction of the oscillation of the lever 112 can be reversed for a selected directional movement of the plus-minus slide 52. In this manner the sign character of the registration in the revolutions counter can be reversed with respect to the sign character of the registration in the accumulator, so that either a multiplier or quotient can be registered in true figures, or complements. Normally, the control arm 123 is urged to the position shown in Fig. 3 by a spring 126 connected between arm 123 and plate 111. In this position of the parts, the revolutions counter will register with the same sign character as the accumulator.

A manual control is provided for determining the position of the control arm 123 with respect to the lever 112 so that either true figure or complementary results can be obtained in the revolutions counter, and in addition, the control can be set so that the revolutions counter will always register with the same sign character irrespective of the sign character of the registration in the accumulator. This latter setting is especially useful in problems where the total number of registrations in the accumulator is desired irrespective of whether they are positive or negative, as, for example, in calculating gradients in highway construction.

Control lever 130 (Figs. 5, 7 and 8) is pivotally mounted by stud 119 on control plate 111, and has a bent and offset lower end 132 provided with an end surface 133 beneath the pin 121, and also provided with a pin 134 overlying an arm 136 pivoted at 137 on plate 111. The free end of arm 136 has pivotally connected thereto at 138 a link 139, which is also pivotally connected at 141 with a cam lever 142. Lever 142 is pivoted by a stud 143 on plate 111 and has its lower arm connected by spring 144 with a suitable stud on plate 111, so that the cam lever 142 is 75

normally urged in a counterclockwise direction to the position shown in Fig. 5, where its lower arm engages a stop pin 146 on plate 111.

The control lever 130 can be adjusted to any one of the three positions illustrated in Figs. 5, 7 and 8, respectively, and is resiliently latched in any such position by means of latch lever 151 pivoted at 152 on plate 111 and having three V-shaped notches 153 for cooperation with a pin 154 projecting laterally from lever 130. The notches 153 are spring-urged into engagement with pin 154 on lever 130 by spring 120 connected between latching arm 151 and centralizing arm 118.

15 Figure 8 shows the lever 130 adjusted to determine registration of like sign character in the accumulator and in the revolutions counter, and it will be noted that in this position, pin 134 has engaged arm 136 and carried it downwardly to effect a similar movement of the cam lever 142 thru link 139, against the tension of spring 144. Thus, cam lever 142 is moved to and held in inactive position and pin 121 remains engaged with arm 113 under the influence of the spring 126.

20 25 If the lever 130 is moved to its extreme left hand position as shown in Fig. 7, end surface 133 thereof engages the pin 121 to move arm 123 upwardly and engage pin 122 with arm 114. In this condition of the parts, the sign character of 30 the registration in the revolutions counter will be opposite to that in the accumulator, so that quotients or complementary multipliers will be registered.

35 If the control lever 130 is moved to its central position as illustrated in Fig. 5, pin 121 remains engaged with arm 113 while cam lever 142 is held in active position by its spring, where its upper end abuts pin 122. With the parts positioned as described and as shown in Fig. 5, movement of 40 plus-minus slide 52 toward the rear of the machine operates, through arm 123 and pin 121, to rock control lever 112 in a clockwise direction and thereby determine positive registration on the revolutions counter. If plus-minus slide 52 is 45 moved forwardly of the machine, pin 122 rides on the end surface of cam lever 142 and moves upwardly into engagement with arm 114, while pin 121 is at the same time moved out of engagement with arm 113. The forward movement of arm 50 123 and pin 122 also serves to effect clockwise oscillation of control lever 112, so that with control lever in its central position control lever 112 is operated in the same manner and positive registration in the counter will take place, irrespective of the direction of movement of the plus-minus slide. Therefore, in this condition the revolution counter serves to count the total number of registrations without relation to their 55 sign character.

60 65 As noted above, this type of operation is particularly useful in calculation of road gradients, where one factor, distance, increases constantly whether or not the road gradient is positive or negative.

65 While I have shown and described my invention in connection with a preferred construction, it is to be understood that the construction can be modified and varied within the scope of my invention as defined in the appended claims.

70 75 I, therefore, claim as my invention:

1. In a calculating machine, a reversible accumulator, uni-directionally operable actuating means therefor, settable plus-minus gears between said actuating means and said accumulator for controlling the sign character of registration

on said accumulator, said gears being movable in either direction from a central inactive position to respective active positions, a revolutions counter, counter actuating means, means controlled by setting of said plus-minus gears for controlling the sign character of the registration on said counter by said counter actuating means, and means including a manually settable control member having a plurality of positions for selectively reversing the control exercised by said plus-minus gears over said counter registration sign character controlling means, and having a position for controlling said last-named means to cause registration of a constant sign character on said counter in any active position of said settable 15 gears.

2. In a calculating machine having an accumulator, a revolutions counter, and respective actuating means therefor; settable means for determining positive or negative registration on said 20 accumulator, means responsive to movement of said settable means for controlling positive and negative registration on said counter, and means including a manipulable control member settable to a position for controlling said responsive means 25 to cause registration of one sign character only on said counter irrespective of the setting of said settable means to cause positive or negative registration on said accumulator.

3. In a calculating machine having an accumulator, a revolutions counter, and respective actuating means therefor; a plus-minus control member movable in opposite directions from a neutral position to control the sign character of the registration on said accumulator, plus-minus control 35 means for said counter controlled by said control member and normally effective to change the sign character of the registration on said counter in response to changes in the sign character of the registration on said accumulator, and a manipulable control mechanism settable to a position for controlling said plus-minus means to cause registration of one sign character only on said counter irrespective of the direction of movement of said plus-minus control member. 45

4. In a calculating machine having an accumulator, a revolutions counter, and respective actuating means therefor; a slide mounted for end-wise movement in either direction to control the sign character of the registration on said accumulator, a lever pivotally mounted intermediate its ends and oscillatable in either direction to control the sign character of the registration on said counter, a connecting link movable to connect said slide to either arm of said lever, and means 50 for determining movement of said link to connect said slide to one arm of said lever on movement of said slide in one direction and to the other arm of said lever on movement of said slide in the other direction, including a cam for controlling 55 movement of said link to connect said slide with said one arm.

5. In a calculating machine having an accumulator, a revolutions counter, and respective actuating means therefor; a slide mounted for end-wise movement in either direction to control the sign character of the registration on said accumulator, a lever pivotally mounted intermediate its ends and oscillatable in either direction to control the sign character of the registration on said 60 counter, a connecting link movable to connect said slide to either arm of said lever, spring means urging said link into engagement with one of said arms, and a cam settable to determine movement of said link to provide for connection of 75

- 5 said slide to one arm of said lever on movement of said slide in one direction and to allow connection of said slide to the other arm of said lever under the influence of said spring means on movement of said slide in the other direction.
6. In a calculating machine having an accumulator, a revolutions counter, and respective actuating means therefor; a slide mounted for endwise movement in either direction to control the sign character of the registration on said counter, a connecting link movable to connect said slide to either arm of said lever, and control means associated with said link for determining connection thereof to one arm of said lever upon movement of said slide in one direction and for determining connection of said link to the other arm of said lever upon movement of said slide in the other direction. 10
- 10 15 20 25 30 35 40 45 50 55 60 65 70 75 80 85 90 95
10. In a calculating machine, an accumulator, accumulator actuating means, settable means for controlling the sign character of registrations on said accumulator, a revolutions counter, counter actuating means, adjustable means for controlling the sign character of registrations on said counter, connecting means from said settable means to said adjustable means whereby the sign character of a registration on said counter can be like or unlike the sign character of the corresponding registration on said accumulator, and manipulable control means for setting said connecting means to determine operation thereof to provide registration of a single sign character on said counter irrespective of the sign character of the registration on said accumulator. 15 20 25 30 35 40 45 50 55 60 65 70 75
11. In a calculating machine, an accumulator, accumulator actuating means, settable means for controlling the sign character of registration on said accumulator including a member movable between a plus position and a minus position, a revolutions counter, counter actuating means, adjustable means for controlling the sign character of said counter including an element movable between a plus position and a minus position, connecting means between said member and said element for controlling the position of said element to be like or unlike the position of said member, and manipulable control means associated with said connecting means to vary the operation thereof by causing adjustment of said element to a single position irrespective of the adjusted position of said member. 35 40 45 50 55 60 65 70 75
12. In a calculating machine, an accumulator, accumulator actuating means, means including a slide movable in either direction from a central position to control the sign character of registrations on said accumulator, a revolutions counter, counter actuating means, means including a lever pivotally mounted intermediate its ends and oscillatable in either direction from a central position to control the sign character of a registration on said counter, means including a link for connecting said slide to either arm of said lever, spring means urging said link into engagement with one of said arms, a manually settable control member associated with said link having a plurality of adjustments for determining control of said lever from said slide, and a cam mounted for movement to and from active position under control of said control member for effecting engagement of said link with the other of said arms, one setting of said control member providing for engagement of said link with said one arm during movement of said slide in one direction and for placing said cam in active position, whereby upon movement of said slide in the other direction said cam becomes effective to engage said link with said other arm. 50 55 60 65 70 75
9. In a calculating machine having an ac-
- cumulator, a revolutions counter, and respective actuating means therefor; a slide mounted for endwise movement in either direction to control the sign character of the registration on said accumulator, a lever pivotally mounted intermediate its ends and oscillatable in either direction to control the sign character of the registration on said counter, a connecting link movable to connect said slide to either arm of said lever, and control means associated with said link for determining connection thereof to one arm of said lever upon movement of said slide in one direction and for determining connection of said link to the other arm of said lever upon movement of said slide in the other direction. 10 15 20 25 30 35 40 45 50 55 60 65 70 75
13. In a calculating machine, an accumulator, accumulator actuating means, settable means movable in either direction from a central position to control the sign character of registrations on said accumulator, a revolutions counter, counter actuating means, other settable means movable in either direction from a central position to control the sign character of a registration on said counter, reversible means for connecting 75

- said settable means for simultaneous movement, whereby movement of one of said settable means controls the movement of said other settable means, spring means yieldably urging said reversible connecting means into one adjusted position thereof, and adjusting means for reversing the operation of said connecting means upon movement of said one settable means in one direction from its central position.
- 10 14. In a calculating machine, an accumulator for receiving both positive and negative registrations, a revolutions counter for receiving both positive and negative registrations, respective actuating means for said accumulator and said counter, settable means for controlling positive and negative registrations on said accumulator, adjustable means for controlling positive and negative registrations on said counter, means for effecting adjustment of said adjustable means in accordance with the setting of said settable means so that like or unlike registrations will be entered in said accumulator and said counter, and manipulable control means cooperatively related to said adjustment effecting means for disabling the normal adjustment therecf in accordance with the setting of said settable means to cause one kind of registration only in said counter for both positive and negative registrations in said accumulator.
- 15 15. In a calculating machine, an accumulator, a revolutions counter, respective actuating means for said accumulator and said counter, settable means for controlling the sign character of registrations on said accumulator, settable means for controlling the sign character of registrations on said counter, common means for operating said settable means, means for causing setting of said counter controlling means reversely with respect to the setting of said accumulator controlling means, and means for disabling said last-named means to cause registration of a single sign character on said counter irrespective of the sign character of registrations on said accumulator.
- 20 16. In a calculating machine having an accumulator, a revolutions counter, and respective actuating means therefor; a plus-minus control member movable in opposite directions from a neutral position to control the sign character of registrations on said accumulator, plus-minus control means for said counter settable to cause both positive and negative registrations thereon, means adjusted by said control member to set said plus-minus control means and cause changes in the sign character of the registration on said counter in response to changes in the sign character of the registration on said accumulator, and control mechanism settable selectively to disable the adjustment of said last-named means by said control member and to cause registration of a single sign character only on said counter irrespective of the sign character of registrations on said accumulator.
- 25 17. In a calculating machine having an accumulator, a revolutions counter, and respective actuating means therefor; settable means for causing either positive or negative registrations on said accumulator, adjustable means for causing either positive or negative registrations on said counter, and control mechanism for effecting adjustment of said adjustable means, said control mechanism including a manually settable control member having one position to adjust said adjustable means to cause like registrations on said accumulator and said counter, a second position to adjust said adjustable means to cause unlike registrations on said accumulator and said counter, and a third position to adjust said adjustable means to cause registrations of a single sign character on said counter irrespective of the sign character of registrations on said accumulator.
- 30 18. In a calculating machine an accumulator, accumulator operating and control means for effecting both positive and negative registrations thereon, a revolutions counter, counter operating and control means for effecting both positive and negative registrations on said counter, means operated by said accumulator operating and control means for causing the sign character of registrations on said counter by said counter operating and control means to change in response to changes in the sign character of the corresponding registrations on said accumulator, and settable means having a normally inactive relation to said counter operating and control means and settable to active position to control said operating means to cause registrations of a single sign character on said counter irrespective of the sign character of corresponding registrations on said accumulator.
- 35 19. In a calculating machine an accumulator, accumulator operating and control means for effecting both positive and negative registrations thereon, a revolutions counter, counter operating and control means for effecting positive and negative registrations on said counter, means operated by said accumulator operating and control means for causing the sign character of registrations on said counter by said counter operating and control means to change in response to changes in the sign character of the corresponding registrations on said accumulator, said counter operating and control means including a manually settable control member therefor having three positions of adjustment, said control member in one of said positions causing like registrations on said counter and said accumulator and in a second of said positions causing unlike registrations on said counter and said accumulator, and means brought into play by said member in the third position of adjustment thereof for varying the action of said counter operating and control means in response to operation of said accumulator operating and control means to cause registrations of a single sign character on said counter irrespective of changes in the sign character of registrations on said accumulator.

ALBERT I. RICHARDS. 65
